WASHING MACHINE

Donald W. Sessions, Lansing, Mich.

Application September 15, 1955, Serial No. 534,568

3 Claims. (Cl. 68—10)

This invention relates to a continuous and progressively fed cylinder clothes washer of the commercial type and is more specifically directed to an improved construction and combination of drive means that is interposed between the washing cylinders and the various rotors carrying such cylinders to provide novel and efficient driving means for said cylinders. The invention herein presented constitutes an improvement over such cylinder driving mechanisms that are associated with the rotors and cylinders in my Patent No. 2,645,914, issued on July 21, 1953, and over the analogous drive means as shown in the Milton L. Neher Patent No. 2,655,021, issued October 13, 1953.

Machines of this character have always presented a problem in moving and driving the respective clothes washing cylinders and in advancing such cylinders from rotor to rotor in such multi-rotor washers and particularly since the rotors normally operate at different rotational velocities. The introduction of an extraction cycle brings in a rotor that is driven unidirectionally at high speed velocity in contrast to adjacent rotors that normally operate at relatively low speeds and may or may not be unidirectional in operation.

It has also been the practice in the past to lock the cylinders to the rotors in their various washing, rinsing, extracting, drying or fluffing stations. This required the alignment of rotors into certain predetermined angular relationships to facilitate further locking of the cylinders to the rotors after each advancement from stage to stage is performed.

The more modern practice in horizontal washers of the continuous progressive type has been to eliminate alignment requirements and to carry out the entire washing cycle without stopping the rotors or cylinders in their progress through the machine by virtue of the concentrically symmetrical designs of the cylinders and by other improvements that directly contribute to the operational phases of these continuous multi-phase types of washers.

Various means have been employed to pass and guide the cylinders along the lane of rotors and across the gaps between such rotors, and more specifically to releasably connect or join the cylinders to the rotors containing the same after each shift of the cylinders. This problem presented the most difficulty during the displacement of the cylinders from slow speed to high speed stages, and vice versa, it being understood that periodic opposite oscillation or rotation of adjacent rotors complicates this transfer problem.

Various frictional means for cooperation between the rotors and the cylinders nested therein have been used such as tracks or ways made of rubber, wood or other wear resisting materials of frictional characteristics. But these tracks or ways do wear and deteriorate through continued use, and also, by reason of continual subjection to water, soaps, water softeners, and washing chemicals which obviously affect the life and efficiency of the tracks and ways causing undesirable maintenance costs and equally costly shut downs of the washing units.

2

It is one of the main objects of the present invention to simplify the continuous washer rotor and cylinder construction in such a manner as to provide effective cylinder revolving means adapted for long life and efficient use under all normal conditions of operation in commercial types of washers of the character noted.

It is another object of the invention to introduce an arrangement for driving the cylinders within the rotors which has the ability to tone down or step up the rotational velocity of the cylinders as they pass between the rotors from stage to stage wherein such adjacent rotors required to operate at widely different velocities or in opposite directions as the case may be when the cylinders are being transferred between rotors.

Other objects relating to the novel features of the present invention shall hereinafter appear in the following detailed description having reference to the accompanying drawings illustrating a preferred arrangement and combination of elements for carrying out the inherent contributions of the present invention and forming a part of this specification.

In the drawings:

Figure 1 is a general diagrammatic layout of a continuous commercial progressive cylinder washing machine embodying the newly designed cylinder rotor combination which is adapted for advancing the cylinders through the machine from stage to stage and also performing the dual function of driving each cylinder or group of cylinders in the various stations of operation in the washer;

Figure 2 is a transverse vertical cross-sectional view taken through the machine substantially along the line II—II in Figure 1 to diagrammatically illustrate certain other details of construction and the general arrangement of the various mechanisms;

Figure 3 is an edge elevational view of one of the improved cylinders utilized in the washer and as it appears when bodily removed from the rotors;

Figure 4 is a fragmentary longitudinal cross-sectional view through the rotor and cylinder combination as taken substantially along the line IV—IV in Figure 1;

Figure 5 is a transverse cross-sectional view fragmentarily showing a portion of the Figure 4 construction as generally seen along the line V—V therein;

Figure 6 is a diagrammatic developed view of a portion of the cylinder surface as seen in a single plane and its cooperative relationship with respect to adjacent rotors and to illustrate the cooperative driving means between the rotors and the cylinders; and

Figure 7 is an end view of one of the rotors per se.

The general layout of the continuous washer installation may best be understood by reference to Figure 1 in the drawings and consists of the washer 1 divided into compartments 2, 3, 4 and 5, together with loading and unloading stations 6 and 7 to be serviced by means of a suitable continuous overhead track system 8 leading from a cylinder loading platform 9 to the washer and away from the latter to a cylinder unloading platform 10.

The compartments 2, 3, 4 and 5 may or may not be divided into smaller divisions to provide different washing and rinsing stages for the cylinders but for the purposes of this invention and for the sake of clarity such extra details have been omitted. Figure 1 illustrates a plurality of rotors 11, 12, 13 and 14 disposed in axial alignment and in the compartments 2, 3, 4 and 5, respectively.

The individual washing cylinders are shown at 15—15 throughout the washer 1 and in the rotors 11 to 14, the entire group of cylinders being arranged for endwise progress through the machine as may be brought about through suitable means such as a hydraulic ram 16 that is controlled by a hydraulic power cylinder 17.

All of the rotors are supported for rotation upon suit-

ably mounted guide rollers 18 and 19 as seen in Figure 2 with certain of said rotors such as 11 and 12 each having a plurality of oppositely disposed buckets 20 and 21 arranged about their periphery to scoop up the water from the baths provided in each compartment where needed. The liquid level is herein maintained below the rotors carrying the cylinders at the washing stages, the level being shown at 22 in Figure 2 so that the solutions may be independently segregated while endwise movement of the cylinders 15 from compartment to compartment and rotor to rotor can be accomplished freely.

The rotors 11, 12, 13 and 14 are driven by means of belts 23, 24, 25 and 26 connected with pulleys such as 27 and 28 secured to drive shafts 29 and 30, the various drives being independent and arranged for different speeds to carry out the washing cycle. As seen in Figure 1, rotors 11 and 12 may be revolved at speeds determined in accordance with the formula set forth in my co-pending application Serial No. 515,626, first in one direction for a set time and then in the other direction, either together or on off-time intervals. Rotor 13 represents an extraction cycle and is usually driven at relatively high speeds in one direction at a rate of approximately 600 R.P.M. or faster. Then a fluffing and drying rotor such as 14 is used and rotated at slower speeds either unidirectionally or reversibly.

In carrying out the advance of the cylinders 15 through the machine from stage to stage, the cylinders 15 have been designated to easily make the transposition from one rotor to the next rotor without changing or interfering with the rotor actuation and without reducing the relative speeds of the rotors or bringing adjacent rotors to similar speeds at change-over intervals. In addition, the cylinders 15 have further been designed to coact frictionally with the rotors for the purpose of driving the cylinders at rotor speeds, over-running speeds in reversible rotor operation, and to conveniently and efficiently make the transition between rotors.

Figures 3 to 7 show the main features associated with the cylinders 15 which contribute to carry out the objects of this new arrangement and coaction between rotors and cylinders. Each cylinder 15 is of the usual cylindrical sheet metal construction having a perforated body 31 with a loading door end 32 and a dead end 33, the door end carrying a friction pad 34, while the dead end carries an antifriction button 35. The cylinders are advanced through the contacting members 34 and 35 under the action of the ram 16, and since the members 34 and 35 make adjacent cylinders rotationally independent, changes in the speed or direction of rotation of the individual cylinders through rotors or from rotor to rotor will not be affected.

Each of the cylinders 15 is provided with frictional driving plates or bands 36 peripherally secured to the cylinder body 31 and between the leading and trailing ends of the cylinder comprising the dead end 33 and door end 32 of the cylinder. The interiors of the rotors are smooth but their diameters are all alike and only slightly larger than the constructional limits of the overall outside diameters of the driving plates or bands 36 as determined at 180° locations with respect to the cylinders. The clearance between the rotors and bands is such as to permit lateral or endwise displacement of the individual cylinders and yet to provide sufficient normal frictional contact due to the weight of the cylinders and clothes, this action also being aided by any off-center loads in the cylinders which loads further act to increase the necessary frictional driving unions between cylinders and rotors.

Assembly or securing of the peripherally situated plates or bands 36 or replacement thereof may be accomplished by attaching the bands 36 to the bodies 31 of the cylinders 15 by screws 37 or through other attachment devices. Furthermore, the bands may be varied in surface area to suit conditions of operation and to properly span the gaps that exist between rotors so that the cyl-

inders are well guided and received by successive rotors and guided between rotors as the cylinders are actuated lengthwise through the washer.

Although units 36 have been defined as bands they are individually spaced about the outer peripheral circumference of the cylinders so as to provide a number of gaps or slots 38 therebetween for the reception of key bars such as 39 that are carried upon the inner periphery of the rotors. In this connection, the key bars 39 may be supplied as a single bar or as multiple bars as shown in Figure 7. These bars, however, are spaced in a predetermined angular relationship with respect to the circumference of the rotors so that they will bear a direct relationship between the positioning of the various friction plates or bands 36 and more specifically in relation to the slots 38 therebetween.

Referring more specifically to Figures 3 and 6, it should be noted that the bands are each provided with tapered sections 40 and 41 so that the adjacent tapered sections 20, 40 and 41 between adjacent plates 36 will diverge outwardly in the direction in which the cylinders are shifted through the machine and that the pair of diverging sections of the bands 36 blend into and form guides in connection with the slots 38 for the reception of the key bars 39. Furthermore, each of the friction plates or bands 36 extend across from face to face of the cylinders. With this construction a cylinder may be moved from rotor to rotor as across the gap 42 between rotors 12 and 13 as shown in Figures 4 and 6, and the advanced 30 portions of the bands will frictionally contact the receiving edge of the rotor 13 while the trailing edges of each of the bands will steadily move out of the rotor 12. It should also be noted, as shown in Figures 4 and 6, that the key bars 39 have their cylinder receiving terminal ends 35 disposed inwardly from the edge 44 of the rotor 13 which gives the leading edges of the bands 36 of the advancing cylinder 15 an opportunity to be frictionally toned downwardly or upwardly in speed depending upon the relative rotational speed of the rotors 12 and 13. In other words, by first causing the cylinders to arrive at some intermediate speed adjustment between rotors before the key bar or bars 39 enter the guide gaps 45 between the bands 36 as the cylinder advances into the rotor and whereby such key bars will eventually find their way into the retaining slots such as 38 to cause a positive drive between the rotors and the cylinders.

By using the wide gap between adjacent plates 36, such as 45, the union between the key bars and the slots 38 is easily accomplished regardless of which direction the cylinders are rotating in relation to the next adjacent rotor and the adjustment immediately takes place in bringing the key bar into alignment with the slots to provide this positive drive between the rotors and cylinders. Obviously, it should be noted that the slots 38 are open through so that the cylinders may advance through the rotor in endwise fashion to the next station or to leave the same rotor and advance into the next adjacent rotor to be keyed to the rotor in the same fashion. Attention is also directed to the fact that when the cylinders are in position in a rotor with the key bars 39 in the slots 38 that reverse rotation of the cylinder under a reversible motor or other suitable drive will cause immediate reversal of the cylinder with a minimum of noise and with a minimum of lost motion between the cylinder and the rotor to thus create a stronger construction and to prevent slapping and banging between the key bars and the bands which was one of the objectionable features encountered in the construction hereinbefore shown in my prior patent No. 2,645,914.

Referring back to Figure 2, it should be noted that the belt drive 24 drives the rotor 12 at a suitable speed through a suitable power drive as by means of a motor connected with shaft 29. As further seen in Figure 2, a rotor 13 which is the extraction cycle unit, is driven by 75 the belt 25 through the pulley 28 on shaft 30. This

drive may be continued by means of a belt or chain 46 connected with a drive pulley or sprocket 47 secured to a shaft 48 that is driven through a suitable changeable speed power transmission 49 that receives its motive power through shaft 50 and coupling 51 from a motor shaft 52 carried by the motor 53. Any suitable change speed or variable speed control such as 54 having a depending hand operated cord or link means 55 may be used for operating the transmission unit 49 in order to obtain a predetermined speed for the extraction rotor 13.

It is, therefore, also contemplated with the present invention to provide suitable variable speed means whereby it is momentarily possible to tone down the speed of one rotor to such an extent as to cut down the speed of one rotor with respect to the other, particularly during the time that the cylinders are shifted through the machine or advanced by means of the ram 16 operated by the hydraulic cylinder 17. Obviously, where the relative speeds between the adjacent rotors are not too great there is no need for a speed reduction in one rotor with respect to the other, but from experience it is more practical to reduce the speed of an extraction rotor in relation to the next adjacent washing or fluffing rotors so as to provide a better transfer situation of the cylinders from one of the rotors into the next of the rotors. Obviously, a direct transfer and driving connection as brought about through the key bars 39 and the bands 36 may be solely utilized, but such action can be supplemented by slowing down the rotor speeds during a transfer of cylinders under certain conditions of operation.

The above description has been directed to a preferred embodiment of the present invention, but it is also possible to make certain changes and alterations in the exact elements herein employed or in the combination of elements herein used without departing from the fundamental concept of this invention. Any such modifications, however, shall be governed by the breadth and scope of the language of the claims appended hereto.

I claim:

1. A washing machine comprising in combination: a rotor, drive means to revolve said rotor; a clothes holding cylinder arranged for guided passage through said rotor; means to transmit revolving motion of said rotor to said cylinder comprising a series of longitudinally extending, circumferentially spaced bars secured to the inner surface of said rotor, a plurality of bands secured to the external surface of said cylinder, each of said bands having portions which taper toward one end of said cylinder, said bands being spaced from each other to provide a slot, said bars being receivable in said slots.

2. A progressive washing machine, comprising in combination: at least two rotors disposed in axial alignment; drive means to revolve each of said rotors; clothes holding cylinders arranged for guided passage through and between each of said rotors; actuating mechanism to move said cylinders through said rotors; means to transmit the revolving motion of said rotors to said cylinders and to guide movement of said cylinders through said rotors comprising a series of longitudinally extending, circumferentially spaced bars secured to the inner surface of each of said rotors, a plurality of bands secured to the external surface of each of said cylinders, adjacent bands being provided with oppositely tapered edges together defining a divergent zone adjacent the leading edge of the cylinder, said adjacent bands having parallel edges adjacent the trailing edges of said bands defining a slot substantially equal in thickness to the thickness of said bars, said slot being parallel to the axis of said cylinders and rotors, the total number of said slots being equal to the number of said bars, said bars being receivable within said slots.

3. A progressive cylinder type washing machine comprising in combination: at least two rotors disposed in axial alignment; drive means to revolve each of said rotors independently; clothes holding cylinders arranged for guided passage through and between each of said rotors; actuating mechanism to move said cylinders through said rotors; means to transmit the revolving motion of said rotors to said cylinders and to guide movement of said cylinders through said rotors comprising a series of longitudinally extending, circumferentially spaced bars secured to the inner surface of each of said rotors, said bars terminating inwardly of the cylinder receiving ends of the rotors to provide an annular zone of receiving the leading portion of said cylinder, a series of bands secured to the external surface of each of said cylinders, said bands being equal in number to the bars, each of said bands having a generally U-shaped section on the leading portion of said cylinder, the ends of said 40 U-shaped section lying parallel with the axis of said rotors and cylinders and with said bars, adjacent bands on said cylinder being spaced to define a divergent zone adjacent the leading portion of said cylinder and a slot substantially equal in thickness to the thickness of said bars, said bars being receivable in said slots.
